UNITED STATES PATENT OFFICE

101,101

DESIGN FOR A CHIME OR SIMILAR ARTICLE

Gisbert L. Bossard, Dayton, Ohio

Application June 27, 1935, Serial No. 57,425

Term of patent 14 years

To all whom it may concern:

Be it known that I, Gisbert L. Bossard, a citizen of the United States of America, residing at Dayton, in the county of Montgomery, State of Ohio, have invented a new, original, and ornamental Design for a Chime or Similar Article, of which the following is a specification, reference being had to the accompanying drawing, forming a part thereof.

Fig. 1 is a front elevational view of the chime showing my design, the surface finish being omitted;

Fig. 2 is a top plan view, and

Fig. 3 is a perspective view, on an enlarged scale, the shading indicating a contrasting color effect.

As shown, the article embodying the design comprises a pair of opposed sounding tubes with a support between the tubes and a front plate in front of the support.

I claim:

The ornamental design for a chime or similar article, substantially as shown and described.

GISBERT L. BOSSARD.
